TUBE ROLLING MILL

Karl A. Nygren and Johannes A. Zschiesche,
Milwaukee, Wis., assignors to Globe Steel
Tubes Co., Milwaukee, Wis., a corporation of
Delaware

Application April 10, 1933, Serial No. 665,358

4 Claims. (Cl. 80—11)

This invention relates to a tube rolling mill capable of advantageous use as a reducing mill although also capable of various other tube rolling operations.

5 Among the objects of the invention are to provide a tube rolling mill wherein the rolls are so mounted, organized and driven as to provide a compact, efficient and durable structure and as to be capable of easily controlled adjustment 10 whereby to vary the reduction effected by any set of rolls or to take up for wear or to throw in or out of action any roll stand, that is, any particular set of cooperable rolls.

Another object is to provide a novel form of 15 driving mechanism for the rolls which, while simple and durable and compactly and closely organized, is highly efficient in operation and insures the driving of the rolls of each set at a synchronous speed.

20 Other objects and advantages reside in certain novel features of the construction, arrangement and combination of parts which will be hereinafter more fully described and particularly pointed out in the appended claims, reference 25 being made to the accompanying drawings, forming a part of this specification, and in which:

Figure 1 is a diagrammatic view in side elevation illustrating a plurality of roll stands or units embodying the present invention and co- 30 related for a tube rolling operation;

Figure 2 is a view in elevation showing one of the roll stands as viewed from line 2—2 of Figure 1, with parts broken away and shown in section for the sake of illustration;

35 Figure 3 is a view in longitudinal section taken on line 3—3 of Figure 2;

Figure 4 is a detail view in section taken on line 4—4 of Figure 2;

Figure 5 is a view in section taken on line 5—5 40 of Figure 4;

Figure 6 is a sectional view taken on line 6—6 of Figure 5;

Figure 7 is a sectional view taken on line 7—7 of Figure 4; and

45 Figure 8 is a fragmentary view showing a portion of the housing in transverse cross section.

Referring to the drawings, it will be seen that the rolling mill comprises a plurality of rolling units designated generally at U, all of identical construction, and mounted upon a common bed B.

Each rolling unit comprises a frame or housing designated generally at 1 and made up of a main frame plate 2 vertically disposed and extending transversely between the rails 3 of the

bed, the frame or housing having supporting shoes 4 integral therewith, interengaged with the members 3 and releasably secured thereto by bolts and nuts 5. An annular flange 6 is integral with or otherwise suitably connected to the plate 2 and to this flange and to the plate 2 a removable side plate 7 is secured by bolts and nuts 8 (see Figure 8). Eyes 9 are secured to webs or extension 6' integral with the frame or housing 1 and are adapted to coact with hooks of hoisting chains or tackle to facilitate handling and positioning of the unit.

Associated with each frame 1 and cover plate 7 are four rolls 10, the rolls being arranged in sets with the members of each set symmetrically disposed with respect to their common plane and with one pair disposed at proper angles to the other as clearly illustrated in Figure 2. Each roll 10 is securely fixed to the outer end of a roll spindle 11. Each spindle 11 is supported 20 for rotation in a roller bearing assembly 12 and a ball bearing assembly 13 (see Figures 3 and 5), the assemblies 12 and 13 of each roll spindle being supported within a bearing housing 14 and being so constituted as to prevent axial shifting 25 of their roll spindle with respect to their bearing housing while providing for free rotation of the spindle.

Each bearing housing 14 is provided with a pair of oppositely extending angular flanges 15 30 extending longitudinally thereof and slidably interfitted with channels or grooves 16 provided on the forward end of a slide or mounting block 17 (see Figures 2, 4, 5 and 7). This adjustable interfitting of the bearing housing of each roll 35 spindle with its slide block provides for adjustment of each roll longitudinally of its axis and such adjustment may be controlled and effected by any suitable means as, for example, by means of an adjusting bolt or screw 18 extending 40 through apertured lugs 19 integral with the slide block 17 and having a threaded portion 20 engaged with a nut 21 integral with its bearing housing 14. The head of the bolt 18 engages one of the lugs 19 and a nut 22 is threaded on the 45 other end of the bolt and engages the other lug 19 to secure the parts in adjusted position.

Each slide 17 is made up of side walls 25 connected by an integral centrally disposed cross member 26 having a forward extension 27 in 50 which the lower channel 16 is formed. A cooperable removable section 28 is bolted to the extension 27 as indicated at 29 and provides the structure in which the upper channel 16 is formed. The side walls 25 have longitudinally extending

guide ribs 30 projecting outwardly therefrom and slidably interfitting in guide-ways 31 formed in the side members 32 of a bracket designated generally at 33 and securely bolted as at 34 to the main frame plate 2 and 7. Flanged lugs 35 integral with the side members of the bracket engage flush against and are bolted to abutments lugs 36 which may be formed integral with the main frame plate 2 and 7 (see Figures 2 and 5). Wear plates 37 and 38 may be interposed between the bracket 32 and the side walls and guide ribs of the slide (see Figure 6).

The central cross member 26 of each slide is provided with a vertical slot 40 extending up through the top thereof and intersected by longitudinal openings 41 formed in the cross member. A notched plate 42 is fitted down in the slot 40 and embraces an adjusting screw 43. The opposite sides of the plate 40 engage the confronting faces of collars 44 integral with or suitably secured to the adjusting screw 43. The threaded portion 45 of the screw 43 is engaged with a nut or threaded bearing 46 formed integral with the bracket 33. To facilitate adjustment of the screws, the rearward end of each is squared or otherwise adapted as indicated at 47 to coact with a suitable tool. A nut 48 is threaded on each threaded portion 45 and secures it in adjusted position.

By adjusting each screw 43 the slide 17 interconnected therewith is moved longitudinally in its guides and in such manner as to adjust the associated roll in the roll plane or toward and away from its cooperable or companion roll. In this way the size of the roll pass is varied, and also provision is made for the taking up of wear as well as for the throwing into and out of action of the rolls of any roll stand or rolling mill unit.

Each roll spindle has the end thereof remote from its roll projecting beyond its bearing housing and connected by a removable and universal coupling 50 with the adjacent end of a drive shaft 51. Split collars 52 which have their sections detachably connected by bolts and nuts or the like embrace the end of each drive shaft 51 adjacent its coupling 50 and although normally maintaining the coupling assembled with its drive shaft and roll spindle also provides for the disconnection of the coupling upon its removal. Each drive shaft 51 is rotatably mounted in bearings 53 provided therefor in a gear box or casing 54 interconnected with and securely bolted to the main frame plate 2 and 7. Beveled gearing 55 connects each drive shaft 51 to a pinion shaft 56 journaled in bearings 57 provided therefor in the gear box 54. Each pinion shaft 56 extends transversely of the main frame or housing at a point adjacent the periphery thereof. Pinions 60 are fixed on the pinion shafts 56 and mesh with a master gear 61, the hub of which is rotatably mounted on roller bearings 62 carried by the hub or annular central structure 63 of the main frame or housing #2.

The master gear 61 of each rolling mill unit is driven from an individual gear unit shown diagrammatically at 65 in Figure 2, the gear unit shaft being coupled to a drive line shaft 66 connected by beveled gearing 67 to a main driving shaft 68 which has a pinion 69 thereon meshing with and driving the master gear 61.

In practice, the rolls being independently adjustable in their respective roll planes may be readily set to provide the desired pass opening and thus vary the reduction effected by any set

of rolls. This same feature provides the take-up required for wear and makes it possible to throw in or out of action any particular roll stand or rolling unit. By removing any collar 52 the loose coupling element 50 may be moved outwardly out of engagement with the free end of its roll spindle 11, so that by removing the fastening means which holds the bracket 33 to the main frame plate, the bracket, its slide and the associated roll, roll spindle and bearing may be independently removed from the set. The rolls are also independently adjustable along their respective axes so as to facilitate alignment or symmetrical disposition of the members of each set of rolls with respect to their common plane. The driving means for the rolls is compactly and closely organized and while simple and durable in construction, is efficient in operation and insures rotation of the rolls of each set at the same speed.

While we have shown and described one construction in which the invention may be embodied, it is to be understood that various changes in the size, shape and arrangement of the parts may be made without departing from the spirit of the invention or the scope of the subjoined claims.

The invention claimed is:

1. A rolling mill comprising a single main housing having gear boxes extending laterally therefrom adjacent its periphery, a passage-way extending centrally through said housing for accommodation of material to be rolled, drive shafts carried by the gear boxes and extending toward the longitudinal axis of said passage-way and radially thereof, gearing within said housing and gear boxes for driving said shafts, a plurality of radial disposed rolls adapted for conjoint rolling action on material passing through said passage-way, means slidably interconnecting said rolls and the outside of said housing, said means rotatably supporting said rolls and providing for individual transverse and axial adjustment thereof while maintaining said rolls with their rotational axis lying in a common plane and flexible driving connections between said rolls and said driving shafts, said means, rolls and flexible driving connections being positioned within the confines defined by the face of the housing and the common plane of the outer faces of said gear boxes.

2. In a rolling mill having a housing for roll driving means and radially deposited rolls outside of said housing positioned for conjoint rolling action on material passing perpendicularly to and centrally through said housing, means for supporting said rolls and providing for individual adjustment thereof while maintaining said rolls with their rotational axis lying in a common plane comprising intermediate members slidably interconnected with said housing for movement back and forth in one line of direction only, bearing members slidably interconnected with one end of said intermediate members and positioned between the outer confines of said intermediate members and the housing, the sliding movement of said bearing members being back and forth in one line of direction only, said latter line of direction being transverse of said former line of direction and spindles rotatably supported against axial displacement by said bearing members, said spindles having one end fixedly supporting one of said rolls and the other end flexibly connected with driving means.

3. The invention set forth in claim 2, characterized by single screw means between said intermediate members and said housing and single screw means between said intermediate members and said bearing members whereby all of said members are adjusted relative to each other and to said housing.

4. The invention set forth in claim 2, characterized in that the intermediate members have at one end a lower protruding jaw and a detachable piece providing a complementary upper protruding jaw secured to said lower jaw by screw means, said jaws slidably interconnecting with the bearing members.

KARL A. NYGREN.
